(57) **CLAIM**

The ornamental design for a fortune glass, as shown and described.

DESCRIPTION

FIG. 1 is a top and front perspective view of a fortune glass showing our new design;

FIG. 2 is a left side view of FIG. 1;

FIG. 3 is a right side view of FIG. 1;

FIG. 4 is a rear view of FIG. 1;

FIG. 5 is a front view of FIG. 1;

FIG. 6 is a top view of FIG. 1; and,

FIG. 7 is a bottom view of FIG. 1.

The broken lines in the drawing depict text on the multi-sided object and form no part of the claimed design.
